CLAIM

The ornamental design for an aerosol cap, as shown and described.

DESCRIPTION

FIG. 1 is a perspective view of an aerosol cap, showing the new design, shown in an environment of use with an exemplary aerosol can;

FIG. 2 is a front view thereof, shown with the exemplary aerosol can removed to show aspects of the design not visible when combined;

FIG. 3 is a back view thereof;

FIG. 4 is a right side view thereof;

FIG. 5 is a left side view thereof;

FIG. 6 is a top view thereof; and,

FIG. 7 is a bottom view thereof.

The broken lines are show for the purpose of illustrating both parts of the article as well as environmental subject matter of an exemplary aerosol can. None of the broken lines form part of the claimed design.
